(57) **CLAIM**

The ornamental design for a set of novelty golf club pens, as shown and described.

DESCRIPTION

FIG. 1 is a perspective view of the first pen of a set of novelty golf club pens (iron) with the cap member in place; FIG. 2 is a perspective view of FIG. 1 in an exploded condition;

FIG. 3 is a front elevational view of FIG. 1;

FIG. 4 is a rear elevational view of FIG. 1;

FIG. 5 is a left side elevational view of FIG. 1;

FIG. 6 is a right side elevational view of FIG. 1;

FIG. 7 is a bottom plan view of FIG. 1;

FIG. 8 is a top plan view of FIG. 1;

FIG. 9 is a perspective view of the second pen of a set of novelty golf club pens (putter) with the cap member in place;

FIG. 10 is a perspective view of FIG. 9 in an exploded condition;

FIG. 11 is a front elevational view of FIG. 9;

FIG. 12 is a rear elevational view of FIG. 9;

FIG. 13 is a left side elevational view of FIG. 9;

FIG. 14 is a right side elevational view of FIG. 9;

FIG. 15 is a bottom plan view of FIG. 9;

FIG. 16 is a top plan view of FIG. 9;

FIG. 17 is a perspective view of the third pen of a set of novelty golf club pens (driver) with the cap member in place;

FIG. 18 is a perspective view of FIG. 17 in an exploded condition;

FIG. 19 is a front elevational view of FIG. 17;

FIG. 20 is a rear elevational view of FIG. 17;

FIG. 21 is a left side elevational view of FIG. 17;

FIG. 22 is a right side elevational view of FIG. 17;

FIG. 23 is a bottom plan view of FIG. 17; and,

FIG. 24 is a top plan view of FIG. 17.
